UNITED STATES PATENT OFFICE.

JOHN O. MORRIS, OF WASHINGTON, DISTRICT OF COLUMBIA, ASSIGNOR TO PLANTERS STEMMING COMPANY, OF WILMINGTON, DELAWARE, A CORPORATION OF DELAWARE.

TOBACCO-STRIPPING MACHINE.

1,257,728.

Specification of Letters Patent. Patented Feb. 26, 1918.

Application filed October 7, 1914. Serial No. 865,523.

To all whom it may concern:

Be it known that I, JOHN O. MORRIS, a citizen of the United States, residing at Washington, in the District of Columbia, 5 have invented new and useful Improvements in Tobacco-Stripping Machines, of which the following is a specification.

This invention relates to machines for stripping tobacco leaves, that is to say, for 10 automatically performing the operation of extracting the stems from the leaves, or of stripping the leaves from the stems, which is now ordinarily performed by hand.

I am aware that machines for the said 15 purpose have heretofore been proposed and patented and, in some instances, have actually been built. I refer to such machines as are disclosed in United States Patents Nos. 1,073,853 to H. C. Hebig, 1,087,039 to my- 20 self, and 1,103,641 to W. G. Woodcock, jr.

All of these machines comprise a pair of 25 stemming or stripping rollers, between which the tobacco leaves are drawn by grippers engaging their stems. This construction necessitates the separation of the rollers to permit the grippers to pass through, and returning them to operative position immediately thereafter, otherwise a portion of the leaf, adjacent to the butt end of the stem, 30 will not be acted upon by the rollers but be wasted. The consequence is that, in order to avoid such waste, the rollers must be returned before the grippers have entirely passed therebetween, so that the teeth on the 35 roller strike the rear ends of the grippers and soon become so much bent and distorted that they no longer perform their function of stripping the leaf, which renders it necessary to stop the machine and substitute fresh 40 rollers.

The machine, which constitutes my present invention, works upon an entirely different principle from that of the machines referred to above, and entirely obviates the 45 difficulty or defect in practical operation which I have just described.

Not only is the durability of the leaf-stripping means greatly enhanced, but the machine is much simpler in its mechanism

and, consequently, cheaper in first cost and 50 more economical in operation.

In the said prior machines, in addition to the impossibility of doing the work required without frequently replacing the leaf-stripping rollers, the further practical defect is 55 found in practice, viz. that there is no automatic feed of the leaves to the grippers, whereby the capacity of the machines is necessarily rendered small while the cost of labor for running them is relatively high. 60

In my present machine, the same means which automatically feeds the leaves to the stem-grippers, is also the leaf-stripping means, and is given an intermittent movement so that it remains stationary while a 65 pair of the grippers seize the stems and pull them out of the leaves, and then moves bodily forward again sufficiently, before another pair of grippers comes around, to present the stems of another set of leaves to 70 the same.

This means is, in the embodiment of the invention which I have at present devised and which is illustrated in the accompanying drawings, in the form of an endless belt 75 of sufficient width to support the leaves thereon and having attached to its outer face, adjacent to one edge, a narrow strip of card cloth, or the like, constituting the stripping means. The drums which carry and 80 drive this belt have their shaft axis inclined upwardly, considered from the front of the machine, so that the edge of the belt carrying the said stripping means is higher than the other edge. The gripper bars are carried, as in the said prior machines, by endless chains and are brought into conjunction close to the said higher edge. The chains are driven continuously while the belt is given an intermittent movement through a mated-gear connection with the chain-driving means. Another belt of less width is mounted above the said higher edge of the main belt and is caused to move in unison with the latter, its purpose being to hold the 85 leaves down on the stripping means while the grippers are withdrawing the stems. The shafts of the drums carrying this

smaller belt are inclined reversely to those of the main belt, so that the space between the two belts is V-shaped in cross section with the larger end of the space toward the 5 front of the machine.

The details of this construction and other accessories of the machine will be understood by the description of the drawings, which will now be given,

10 Figure 1 is a side elevation,

Fig. 2 a front elevation, and

Fig. 3 a plan view, of the complete machine, while

15 Fig. 4 is a sectional view, on a larger scale of the two belts and the gripper mechanism.

The gripper bars 5, 5, are carried by the endless chains 6, 6, passing around the sprocket wheels mounted on shafts which are journaled in the side frames 1, 1.

20 This part of the machine is substantially like the corresponding parts of the said patented machines and will readily be understood from the drawing without an extended description. The principal difference in the

25 present construction is that, while the chains pass over large sprocket wheels 4, 4, at the rear end of the machine, and which are geared together and driven from a suitable source of power, shown as a belt pulley and

30 pinion, at the front end the chains pass over small sprocket wheels 3, 3, of which there are two pairs for each chain, the object being to reduce the distance which the stems must project over the edge of the belt in order to be seized by the gripper-bars carried by said chains.

35 It will readily be seen that, if the sprocket wheels at the front end were as large as those at the rear end, or as those shown in the said patents, the meeting plane 40 of the pairs of gripper bars would be considerably farther away from the edge of the belt than when the smaller sprocket wheels of the present machine are used.

The uppermost pair of the said small 45 sprocket wheels 3, 3, are carried on a shaft 8, which extends through from one side frame to the other, and the same is true of the shaft 9 of the lowermost pair of small sprocket wheels, and each of said shafts 50 extends beyond one of said side frames and is operatively connected to the belt-driving mechanism, hereinafter to be described.

The chains 6, 6, run in guides formed in the central members 10, 10, of the side 55 frames 1, 1, whereby the coöoperating pairs of gripper bars 5, 5, are caused to maintain a firm grip on the stems while they are pulling them out of the leaves, and the backs of the gripper bars are truss-shaped, as 60 shown at 11, to prevent their springing apart in their center portions.

It will be noticed that the intermediate pairs of sprocket wheels 3 are farther advanced, toward the front of the machine,

than the upper and lower pairs, the purpose 65 of this being to bring the paths of the gripper-bars, as they approach each other, as close as possible to the edge of the feeding and stripping belt 12, so that said bars will seize hold of the stems projecting over the 70 edge of said belt, as shown in Fig. 4, without the necessity of advancing the leaves, transversely of the belt, to cause the stems to be seized by the gripper-bars, as they 75 come together.

13 represents the strip of card cloth, or the like, carried upon the rear and higher edge of the belt 12, and which constitutes the means for retaining the leaves while the stems are pulled out, in other words, the 80 means for stripping the leaves from the stems.

The belt 12, the upper side of which runs 85 from right to left, looked at from the front of the machine, is extended a sufficient distance to the right, as shown in Figs. 2 and 3, to permit the leaves to be laid thereon with the ends of the stems abutting against a gage board 14. The drums 15 and 16, which carry the belt, have their shafts inclined upwardly from the front to rear, both for the purpose of making the plane of pull 90 on the stems at an angle to the plane of the stripping means, as well as to provide sufficient space for the stripped leaves between the surface of the belt 12 and that of the belt 17, which is reversely inclined, and has a roughened surface 18 on its inner edge to assist in holding the leaves down upon the stripping means 13. Said surface may be 95 a strip of card cloth, a piece of rubber, or even the surface of the belt itself. The belt 17, which extends only in front of that portion of the machine which carries the gripper-bars, is carried by the drums 19 and 20, the shafts of which are mounted in a pair of cast yoke-frames 21, 21, hung upon the 100 shaft 8 and held in adjusted angular position by the screws 22, 22, supported from arms 23, 23, projecting from the top of the 105 side frames 1, 1.

The shaft of the drum 15 of the lower belt is mounted in a similar yoke-frame 24, 110 hung upon the shaft 9 and held in adjusted angular position by screws 25, 25, supported by a standard 26. The shaft of the drum 16, at the other end of said belt, is supported in a similar yoke-frame 24, pivotally supported on another standard 26 and held in 115 adjusted position by similar screws 25.

120 It must be understood that the means just described for supporting and adjusting the belt drums is shown by way of example only, as other adjusting means may be used. Also, the most suitable angle having once been determined, it may not be necessary to provide any adjusting means at all, in which case the yoke-frames 21 may be cast integral

with the side-frames, and the yoke-frames 24 with their supporting standards or tables 26, or be otherwise fixedly supported. Means may also be provided to adjust the tension of the belts, such means not being shown in the drawings, which are merely for the purpose of illustrating an operative means or combination of parts for carrying out the operation of stripping tobacco, according to the present invention.

The belt drums 15 and 16 are provided with flanges 27 on their lower ends, as shown in Figs. 1 and 2, and means are provided to prevent the belt 12 from climbing toward the higher ends of said drums, or moving laterally toward the path of the gripper-bars. Such means may consist of a strip 28, secured to the front edge of said belt, and a recessed or bent bar 29, hooked over or engaging the rear side of said strip, said bar having a tubular shank 30, adjustably supported on a standard 31. To prevent the lower belt from sagging and the upper belt from yielding upwardly, during the stripping operation, bars 32, see Fig. 4, are provided to bear against the inner faces of the belts, adjacent to their operative edges, said bars being provided with or carried between the ends of pairs of arms 33, 33, mounted on the stub shafts of the intermediate sprocket-wheels 3, 3, and held in adjusted position thereon by set screws 34, 34. If preferred, said arms may be spring-pressed toward the belts.

To provide for the separation of the unstripped or only partially stripped leaves, of which there will inevitably occur a certain number in the operation of the machine, from the completely stripped leaves, I provide a small corrugated roller 35, carried by a vertical shaft over the belt 12 near its left or delivery end and rotated, by the pairs of beveled gears 36 and 37, sprocket wheels 38 and 39 and chain 40, from the shaft 8, in a right-hand direction, whereby the unstripped leaves are caused to be delivered off the lower portion of the belt, while the stripped leaves, which are of course balled up and lie on and adjacent to the stripping means 18, pass off the rear portion of the belt, and are received in a separate compartment of a receptacle 52, see Fig. 3, from the unstripped leaves. A comb 51, or the like, may be provided on the edge of the receptacle to assist in removing the stripped leaves from the belt. The roller 35 may be made adjustable on its shaft to accommodate variations in the angle of the belt surface. The bevel gears and their shafts are supported by a bracket 41, projecting laterally from the side-frame 1, and a tubular arm 42, extending at right angles from said bracket. Other means, such as belts, may be used to drive the roller 35.

There remains to be described the connections by which the drums 15 and 19 of the belts 12 and 17 are driven intermittently from the shafts 9 and 8. As these connections are the same in both cases, I will describe those for the lower belt drive, and use the same reference numerals for the corresponding elements of the upper belt drive.

A spur pinion 43, on the shaft 9 (or 8), meshes with and drives a spur gear 44, the shaft 45 of which is journaled in the yoke-frame 24 (or 21). On the shaft 45 is also mounted a mutilated spur gear 47 having, for example, teeth cut in only one-third of its periphery. Gear 47 meshes with and drives intermittently a pinion 48, the periphery of which has a concave to receive the smooth portion 46 of the periphery of the gear 47, and the shaft 49 of which is likewise carried by the yoke-frame 24 (or 21). The shaft 49 carries one of a pair of bevel gears 50, the other of which is on the shaft of the drum 15 (or 19).

The bevel gears 50 being of equal size and the pinion 48 considerably smaller than the mutilated gear 47, it will be seen that the belts are driven rapidly during, say, one-third of a revolution of said gear 47 and of the gear 44 on the same shaft 45, during which time pinion 43 and shaft 9 (or 8) of the sprocket-wheel 3 will have made several revolutions. The gripper-bars will, of course, be spaced at such a distance apart on their chains that a pair of them will come into conjunction to grip the stems every time the feed of the belts stop, and the ratio of the gearing described above will be such that the belts will be fed forward again as soon as the stems of one set of leaves have been pulled out, so as to bring another set of leaves into position for the next set of grippers. It will be seen that the gripper bars draw the stems through the cardcloth longitudinally of said stems, there being no transverse displacement thereof during the stripping operation.

Means are of course provided to enable the operator to start and stop the machine as desired.

The operation of the machine having been fully disclosed in the first part of the specification and in the course of the above description of the machine, it is believed not to be necessary to give a résumé of it here.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the lan-

guage used in the following claims is intended to cover all of the generic and specific features of the invention herein described, and all statements of the scope of 5 the invention which, as a matter of language, might be said to fall therebetween.

Having thus described my invention, what I claim is;

- 10 1. A tobacco stripping machine comprising, in combination, a belt, leaf-stripping means associated with said belt, stem-gripping means traveling at right angles to said belt and means to drive said belt and stem-gripping means in timed relation.
- 15 2. A tobacco stripping machine comprising, in combination, leaf-stripping means, stem-gripping means traveling substantially at right angles to said leaf-stripping means for drawing the stems through said leaf-stripping means without transverse displacement of said stems, and means to drive each of said means in timed relation.
- 20 3. A tobacco-stripping machine comprising, in combination, leaf-stripping means, means coöperating with said means for holding leaves in engagement therewith, stem-gripping means traveling substantially at right angles to said stripping means and means to drive said stem-gripping means continuously and said stripping means and holding means intermittently.
- 25 4. A tobacco stripping machine comprising, in combination, a belt provided with leaf-stripping means adjacent one edge thereof, continuously driven chains running at right angles to said belt, a plurality of gripping-bars carried by said chains, and connections between said chains and belt for driving the latter intermittently in timed relation with the former.
- 30 5. A tobacco stripping machine comprising, in combination, a belt provided with card-cloth or the like along one edge, a co-operating belt to press leaves down onto said card-cloth, and means to engage the stems of the leaves projecting from between said belts and withdraw them from the leaves.
- 35 6. In a tobacco-stripping machine, a feed belt provided with card teeth or the like along one edge, means to support said belt with its upper surface inclined downwardly from said edge, a gage adjacent to said edge, for a portion of the length of said belt, whereby the stems of the leaves placed on 40 the belt will project uniformly beyond said edge, gripping means for said stems traveling at right angles to said belt from a point adjacent to said edge and means to drive said gripping means and belt in timed relation.
- 45 7. A tobacco stripping machine comprising, in combination, means for simultaneously conveying a plurality of leaves into and holding each of them in a position to be stripped, means traveling at right angles 45 to the direction of travel of said conveying means for gripping the stems of a plurality of leaves, and connections between said means to cause them to move in timed relation.
- 50 8. A tobacco-stripping machine comprising an upper pair and a lower pair of sprocket chains, a gripper-bar carried by each of said chains, operatively driven and connected sprocket wheels for said chains 70 at the rear end of the machine, four pairs of relatively small sprocket wheels to guide said chains at the front end of the machine, whereby said gripper-bars are brought rapidly into close proximity as their carrying chains pass around the central pairs of small sprocket wheels, a transversely inclined feeding belt mounted with its higher edge closely adjacent to said central pair of small sprocket wheels, means on said belt, adjacent to its said higher edge, to engage and strip the leaves from the stems as the latter are pulled out by said gripper-bars, means, operatively connected with said chain-driving sprocket-wheels, to drive said belt intermittently, means to assist in positioning the tobacco leaves on said belt so that their stems will project beyond said higher edge sufficiently for said gripper-bars to seize the same, means to hold the leaves down on the 85 said stripping means while said gripper-bars are acting to pull out the stems, and means to separate any unstripped or broken leaves from the stripped leaves.
- 55 9. In a tobacco-stripping machine of the 100 class described, the combination with the leaf-conveying-and-stripping belt and the stem-gripper-bar-carrying chains, traveling normally to said belt, of a gage to enable the operator to position the leaves on said belt 105 with their stems projecting a substantially uniform distance beyond the rear edge thereof, two pairs of sprocket-wheels of small diameter for each pair of said chains in the front portion of their travel, the intermediate pairs of said wheels being located closely adjacent to said belt edge, whereby the gripper-bars, carried by said chains, are enabled to seize the ends of said projecting stems, and means to drive said belt and 110 chains in timed relation.
- 60 10. In a tobacco-stripping machine of the class described, the combination with the leaf-conveying-and-stripping belt and the stem-gripper-bar-carrying chains, traveling 115 normally to said belt, of a gage to enable the operator to position the leaves on said belt with their stems projecting a substantially uniform distance beyond the rear edge thereof, so that the gripper-bars will seize the 120 ends of the stems, drums carrying said belt and driven from said chains so as to move said belt forward after each stripping operation to bring a fresh set of leaves in position to be stripped by the next succeeding 125

pair of gripper-bars, and means to prevent lateral movement of said belt toward said gripper-bars.

11. In a tobacco-stripping machine of the class described, the combination with the leaf-conveying-and-stripping belt and the stem-gripper-bar-carrying chains, traveling normally to said belt, of a gage to enable the operator to position the leaves on said belt with their stems projecting a substantially uniform distance beyond the rear edge thereof, so that the gripper-bars will seize the ends of the stems, drums carrying said belt and driven from said chains so as to move said belt forward after each stripping operation to bring a fresh set of leaves in position to be stripped by the next succeeding pair of gripper-bars, means to hold the said rear edge of the belt against lateral or vertical movement throughout the portion thereof in front of the path of said gripper-bars, and means located above the portion of said belt, which has passed beyond the said path, to divert any unstripped leaves toward the front edge thereof, whereby such leaves can be delivered separately from the stripped leaves.

12. In a tobacco-stripping machine of the class described, the combination with the leaf-conveying-and-stripping belt, of drums supporting said belt, the shafts of said drums being inclined downwardly toward the front of the machine, a frame extending at right angles to said belt, pairs of sprocket wheels supported on said frame, pairs of chains mounted on said wheels, means to drive the latter at a constant speed, gripper-bars carried by said chains, a yoke-frame hung on the shaft of one pair of said sprocket wheels and in which the shaft of one of said drums is journaled, and a gear train connecting said shafts and comprising a mutilated gear and pinion, whereby the drum shaft is intermittently driven from said sprocket-wheel shaft.

13. In a tobacco stripping machine of the class described, the combination with the leaf-conveying and stripping belt, of drums supporting said belt, the shafts of said drums being inclined downwardly toward the front of the machine, a frame extending at right angles to said belt, pairs of sprocket wheels supported on said frame, pairs of chains mounted on said wheels, means to drive the latter at a constant speed, gripper-bars carried by said chains, a yoke-frame hung on the shaft of one pair of said sprocket wheels and in which the shaft of one of said drums is journaled, a presser belt mounted above said feeding and stripping belt, drums supporting said presser belt, yoke-frames hung on the shaft of another pair of said sprocket wheels and supporting the shafts of said drums, means on said frame to suspend said yoke frames so

that said shafts will be inclined upwardly toward the front of the machine, and a gear train carried by one of said yoke frames and connecting said sprocket wheel shaft to said drum shaft, said train including a mutilated gear and pinion and being similar to that driving the drum shaft and the feeding and stripping belt, whereby said presser belt moves in unison therewith.

14. A tobacco stripping machine comprising, in combination, a belt on which leaves are placed with their stems projecting beyond one edge thereof, a strip of card-cloth secured to said belt adjacent said edge, means supporting said edge to prevent sagging, means above said edge to press leaves upon said card-cloth, means to drive said belt intermittently, and means to seize the stems and withdraw them from the leaves while said belt is stationary.

15. In a tobacco-stripping machine, the combination of a belt on which the leaves are placed with their stems projecting beyond one edge thereof, a strip of card teeth secured to said belt adjacent said edge, stem-gripping means traveling at right angles to said belt to seize said projecting stems and draw them out of the leaves and a driven roller mounted vertically above said belt to separate any unstripped leaves from those that have been properly stripped.

16. A tobacco stripping machine comprising, in combination, means for simultaneously conveying a plurality of leaves into and holding each of them in a separate position to be stripped, means traveling at right angles to the direction of travel of said conveying means for gripping the stems of a plurality of leaves, and connections between said means to cause them to move in timed relation.

17. A tobacco stripping machine comprising, in combination, means for conveying leaves into and holding them in a position to be stripped, a member having flexible teeth for stripping said leaves, stem gripping means traveling at right angles to the direction of travel of said conveying means, and connections between said means to cause them to move in timed relation.

18. A tobacco stripping machine comprising, in combination, an element having carding teeth thereon, means for drawing the stems of leaves through said teeth, means to hold leaves in position to be stripped by said teeth, and means to move said element bodily from a position where leaves may be laid upon said teeth to a position where the stems will be grasped by said drawing means.

19. A tobacco stripping machine comprising, in combination, leaf-stripping means, a belt co-operating with said means for holding leaves in engagement therewith, means adjacent said leaf-stripping means for guid-

ing said belt, means associated with said guiding means for adjusting the position thereof with respect to said leaf-stripping means, and stem-gripping means for drawing the stems through said leaf-stripping means longitudinally of said stems.

5 In testimony whereof I have hereunto set

my hand in presence of two subscribing witnesses.
